UNITED STATES PATENT OFFICE.

JOHN J. RUDDICK AND CHARLES E. RAND, OF NEWTON, MASSACHUSETTS, ASSIGNEES, BY DIRECT AND MESNE ASSIGNMENTS, TO UNITED STATES ELECTRIC SIGNAL COMPANY, OF PORTLAND, MAINE, AND NEWTON HIGHLANDS, MASSACHUSETTS.

STREET-RAILWAY SIGNALING SYSTEM.

SPECIFICATION forming part of Letters Patent No. 684,952, dated October 22, 1901.

Application filed February 27, 1899. Serial No. 706,929. (No model.)

To all whom it may concern:

Be it known that we, JOHN J. RUDDICK and CHARLES E. RAND, of Newton, in the county of Middlesex and State of Massachusetts, have 5 invented an Improvement in Street-Railway Signaling Systems, of which the following description, in connection with the accompanying drawings, is a specification, like characters on the drawings representing like parts.

10 Our invention is an improvement in railway-signals, being particularly adapted for trolley-lines, such as are commonly used for street-railways, although it is not restricted thereto.

15 The details of construction and operation of our invention will be pointed out in the course of the following description, and the invention will be more particularly defined in the appended claims.

20 In the drawings, Figure 1 is a diagrammatic view showing a portion of track in plan for convenience in explaining our invention. Fig. 2 is a transverse section of one of the signal mechanisms, taken on the line 2 2, Fig. 25 4. Fig. 3 is a perspective view of a portion of the mechanism. Fig. 4 is a transverse section taken on the line 4 4, Fig. 2; and Fig. 5 is a transverse section of one of the trolley-contacts. Fig. 6 is a diagram illustrating the 30 method of operation.

Referring to Fig. 1, *a* designates the main track, along which are usual turnouts *a'* *a''*, between which, it will be understood, is one block of our block-signal system, and the signal mechanisms will be conveniently located, as at station 1 and station 2, these mechanisms being operated by suitable contacts, herein indicated at *a*³, for the trolley to engage.

35 40 At the stations 1, 2, &c., are the signal-boxes, (shown in Figs. 2 to 4 at *b*,) each box containing two sets of electromagnets *b'* *b''*, which are affected every time a trolley passes under a contact *a*³, the electromagnets *b'* serving to attract an armature-lever *b*³, pivoted at *b*^{3x} to a bracket *b*⁴ in the bottom of the box, and the electromagnets *b''* serving to attract similar armatures *b*⁵, likewise pivoted

in the bottom of the box. The armature *b*³ carries a gravity-pawl *b*⁶ at its upper end, 50 provided with a hook *b*⁷, arranged to engage a ratchet-wheel *b*⁸, fast on a shaft *b*⁹, journaled in the sides of the box, as clearly shown in Fig. 4. The armature *b*⁵ carries a push-pawl *b*¹⁰, arranged to engage a ratchet *b*¹², likewise fast on the shaft *b*⁹, and at some convenient place, herein shown as just beyond the ratchet *b*¹², is a dwell-wheel *b*¹³, engaged by a detent or friction lever *b*¹⁴, pivoted at *b*¹⁵ to the side of the box and held down by a 55 spring *b*¹⁶, regulated by a thumb-nut *b*¹⁷, operating against a bracket *b*¹⁸, this dwell serving to prevent accidental or undue movement of the ratchets. Also on said shaft is mounted a circuit-making device, shown as 60 a disk *b*¹⁹, having a metallic contact-surface *b*²⁰ to engage two spring-contacts *b*²¹, so that as long as the spring-arms *b*²¹ are in engagement with the contact *b*²⁰ the signal (which may be an incandescent light of suitable 65 color) will glow, whereas when the arms *b*²¹ are in the air-gap *b*²² the circuit will be broken and the signal will not glow. Each armature-lever is operated in a direction contrary to the electromagnets by a spring *s*, held by 70 a threaded bolt *b*²³ and regulated by a thumb-screw *b*²⁴, operating against a bracket *b*²⁵, and is regulated as to the length of its throw or stroke by a set-screw *b*²⁶. The armature *b*³ is provided with a pin *b*²⁷, which serves to 75 complete the connection between two contact-springs *b*²⁸, mounted adjacent the spring *b*²¹, but extending in an opposite direction. The trolley-contact *a*³ is shown in detail in Fig. 5, and comprises a metallic hood *a*⁵, having diverging wings *a*⁶, flaring at their ends *a*⁷, in order to receive the trolley-wheel *w* rigidly and certainly.

Referring now to Fig. 6, the wiring and manner of operating our improved box-signal system will be clearly understood, the magnets and box mechanism being indicated for each end of the block and the track *t* and trolley feed-wire or source of current-supply *f* being indicated with a car *k* and its trolley 95 in usual position between the two.

The circuit of the electromagnets b' is completed by wires $r' r'$, leading, respectively, to the contact a^3 and to the feed-wire f .

The lamp or signal circuit (the lamp or signal being indicated at m) is as follows: A wire r^2 taps the feed-wire and connects with one of the springs b^{21} , and from the other spring b^{21} a wire r^3 leads to the electromagnets b^2 , and thence a wire r^4 connects with one of the springs b^{28} , and from the other spring b^{28} a wire r^5 connects to the signal m and thence to the rail t or ground.

In view of the above explanation the operation of our invention will be readily understood.

As the car proceeds along the track from left to right, we will suppose, as the trolley comes into contact with the hood at a^3 it thereby energizes the electromagnets b' , which attract the armature b^3 , and through the hook b^7 rotates the ratchet-wheel b^8 and its shaft b^9 , so as to engage the ends of the springs b^{21} with the contact b^{20} , thereby completing the lamp-circuit and setting the signal m at "danger." As the car continues and reaches the end of the block at the position indicated at the right, Fig. 6, it again completes the circuit by engagement of its trolley with the contact a^3 , and this time as it energizes the electromagnets b' of the right-hand box or outgoing end of the block the movement of the armature b^3 toward the electromagnets carries the pin b^{27} out of engagement with the springs b^{28} and instantly breaks the circuit, which includes the electromagnets b^2 of the first signal-box and the box at the incoming end of the block, and thereby permits the armature b^5 thereof to be moved forward by its spring s , and as this armature carries the push-pawl b^{10} the result is that the shaft b^9 is reversely rotated one notch by the engagement of said pawl with the ratchet-wheel b^{12} . This restores the wheel b^{19} to its original position, as shown in Fig. 3, and carries the contact b^{20} thereof out of engagement with the springs b^{21} , so that the circuit including them is broken and the signal m restored to "safety." If now instead of having the block occupied by one car only, let it be supposed that a series of cars—six, for instance—are permitted to enter the block before any leaves the block. It will be evident that as each car enters the block it will energize the electromagnets b' of the entrance signal-box at the left-hand end of the block, so that the shaft b^9 will be turned over to the left six notches by the action of the hooked pawl b^6 , and as these cars leave the block they will successively operate the shaft b^9 of said entrance-box one notch at a time in a reverse direction until when the last car leaves the shaft b^9 will have been rotated over to the right the same six notches, thereby leaving the parts in their original position and restoring the right-hand signal to "safety" again.

While we have shown and described our invention in all the details of its preferred

embodiment, we wish it understood that we are in no wise limited to its details, inasmuch as many changes and modifications may be resorted to within the spirit and scope of our invention.

Our invention therefore comprises in its broadest aspect a block-signaling system for railways including two independent circuits each having a magnet therein and one of said circuits having in addition a signal device and a contact-maker, combined with a step-by-step device operated, respectively, by the armatures of the two magnets in opposite directions, and means operated by a car entering the block to momentarily close one of said circuits—to wit, the one which has not the signal device therein.

The invention herein illustrated comprises a block-signal system including a signal-circuit having a magnet therein and a signal device, said signal-circuit being provided with normally open and normally closed contacts, the normally closed contacts being between the pin b^{27} on armature b^3 and the spring b^{29} and the normally open contacts being between the two spring-plates or contact-pieces b^{21} . Means are also provided to close the normally open contacts as a car passes into the block, whereby the signal device is operated and the magnet in said signal-circuit is energized, and to open the normally closed contacts as the car passes out from the block, whereby the signal device is restored to "safety" and the magnet in the signal-circuit is deenergized, the deenergizing of the magnet operating to restore the normally open contacts to their normal condition.

Having described our invention, what we claim as new, and desire to secure by Letters Patent, is—

1. In a block-signal system, a series of signal-operating devices, one of said devices being at each block, and each device comprising two armatures, magnets for operating said armatures, said magnets being in independent circuits, a signal in one of said circuits, a step-by-step device operated respectively by said armatures, a contact-maker in the signal-circuit operated by said step-by-step device, and means to momentarily close the other of said circuits and energize the magnet therein when a car enters the block, and to open the signal-circuit when a car leaves the block, whereby as a car enters any block, the contact-maker in the signal-circuit for that block is operated to close the said signal-circuit, said circuit remaining closed until the car leaves the block, when the said circuit is opened.

2. In a block-signal system, a series of signal-operating devices, one of said devices being situated at each block, each of said devices comprising two armatures, magnets for operating said armatures, said magnets being in independent circuits, a signal in one of said circuits, a step-by-step device operated in alternate directions by said arm-

tures respectively, a contact-maker in the signal-circuit operated by said step-by-step device, means operated by a car entering the block to close the other of said circuits, where-
5 by the magnet therein is energized, and the contact-maker operated to close the signal-circuit, means operated by said last-named magnet when energized to open the signal-circuit of the block from which the car has
10 just passed.

3. A signal mechanism comprising a plurality of armatures, electromagnets for operating the same, feed mechanisms operated respectively by said armatures and in opposite directions, a contact-maker actuated by said feed mechanisms, a signal-circuit controlled by said contact-maker, a second signal-circuit including one of said armatures, and a make-and-break device for said last-men-
15 tioned circuit operated by the movement of the armature of one of said electromagnets, substantially as described.

4. A signal mechanism, comprising two armatures, electromagnets for operating the same, and two pawl-and-ratchet mechanisms operated respectively by said armatures and in opposite directions, a contact-maker actuated by said pawl-and-ratchet mechanisms, and a signal-circuit controlled by said con-
25 tact-maker, a second signal-circuit including one of said armatures, and a make-and-break device for said last-mentioned circuit operated by the movement of the armatures of one of said electromagnets, substantially as
30 described.

5. In a signal mechanism comprising two armatures, electromagnets for operating the same, and two pawl-and-ratchet mechanisms operated respectively by said armatures and
35 in opposite directions, a contact-maker actuated by said pawl-and-ratchet mechanisms, a signal-circuit controlled by said contact-maker, said circuit including a visual signal and also one of said magnets.

45 6. A signal mechanism comprising two armatures, electromagnets for operating the same, one armature carrying a push-pawl and the other armature carrying a pull-pawl, a ratchet-wheel for each of said pawls, a con-
50 tact-maker operated by said ratchet-wheels, an electric signal-circuit including a visual signal and two independent contacts to be engaged by said contact-maker, said circuit

also including one of said magnets, and means for energizing said electromagnets.

55

7. In a block-signal system for railways, two electromagnets each having an armature, said magnets being in independent circuits, one of said circuits including a signal device, means operated by a car entering a block to 60 momentarily close the other of said circuits, a step-by-step device operated respectively by said armatures in opposite directions, and a contact-maker in the signal-circuit, said contact-maker being actuated by said step- 65 by-step device.

8. In a block-signal system, a signal-circuit including an electromagnet and a visual-signal device, said circuit having normally open and normally closed contacts, means to close 70 said normally open contacts as a car passes into the block, said contacts remaining closed until the car passes out of the block, whereby the magnet is energized and the signal device displayed, and means to open said nor- 75 mally closed contacts when the car leaves the block, the breaking of the circuit de-energizing the magnet, and means controlled by said magnet for restoring the normally open contacts to their normal condition when the mag- 80 net is de-energized.

9. In a block-signal system, a signal-circuit including an electromagnet and a visual-signal device, said circuit having normally open and normally closed contacts, means to close 85 said normally open contacts as a car passes into the block, the said contacts remaining closed until the car passes out of the block, whereby the magnet is energized and the signal device is displayed, means to momenta- 90 rily open said normally closed contacts when a car leaves the block, the breaking of the circuit momentarily de-energizing the magnet, and means controlled by said magnet for re- 95 storing the normally open contacts to their open condition when the last car has left the block.

In testimony whereof we have signed our names to this specification in the presence of two subscribing witnesses.

JOHN J. RUDDICK.
CHARLES E. RAND.
